[57] CLAIM

The ornamental design for an electric fish hook sharpener, as shown.

DESCRIPTION

FIG. 1 is a perspective of the electric fish hook sharpener, the design of the present invention;

FIG. 2 is a side elevation of the electric fish hook sharpener of FIG. 1;

FIG. 3 is a side elevation of the electric fish hook sharpener of FIG. 2, turned ninety degrees (90°);

FIG. 4 is a top plan view of the electric fish hook sharpener; and

FIG. 5 is a bottom plan view of the electric fish hook sharpener as oriented in FIG. 3.

FIG. 2

FIG. 3

FIG. 4

FIG. 5
